UNITED STATES PATENT OFFICE.

LEWIS E. SANDSTROM, OF REXBURG, IDAHO, ASSIGNOR OF ONE-FOURTH TO WILLIAM H. L. HOWARD, OF WASHINGTON, DISTRICT OF COLUMBIA.

AUTOMOBILE LAMP.

Application filed September 2, 1920. Serial No. 407,601.

To all whom it may concern:

Be it known that I, LEWIS E. SANDSTROM, a citizen of the United States, residing at Rexburg, in the county of Madison and State of Idaho, have invented certain new and useful Improvements in Automobile Lamps, of which the following is a specification.

My invention relates to improvements in automobile lamps and refers particularly to 10 means for preventing the glare from the light of the lamp.

The main object of my invention is the construction of a lamp of peculiar design capable of reflecting the rays of the lamp in 15 a downward and forward direction upon the roadbed, utilizing all the rays cast from the light and directing them in the desired direction, no rays being reflected upward from the lamp, and being of extremely 20 simple, durable and inexpensive construction.

Another object of my invention is the construction of a reflector having polished surfaces, of such peculiar design, that may 25 be adapted and attached to lamps at the time of manufacture or to lamps already in use and which will attain the necessary object in a practical and efficient manner.

With these objects in view, my invention 30 consists in certain details of construction and combination of parts, substantially as shown, described and claimed, it being understood that any changes may be made in the construction within the scope of my claims.

In order that the details of construction 35 may be understood and the advantages which accrue from the use of my invention, I have shown in the accompanying drawings a structure embodying my invention.

Fig. 1, represents a central sectional view 40 with my improvements applied and shown in side elevation.

Fig. 2, represents a front view of my invention, shown in elevation.

Referring by letter to the drawings, in 45 which similar letters of reference are used to designate the same parts in the two views:

The letter A designates the reflector of the 50 lamp, constructed of metal and pressed into such shape that the lower portion of the reflector assumes the form shown at B and further represented by the dotted line below D, the electric incandescent lamp. B, the lower portion of the reflector A, is provided

with an opening E thru which the base of 55 the incandescent lamp D passes.

Attached to B by means of solder or other practical means is the metal, circular reflector C, which forms the principal feature of my invention. This reflector, C, entirely 60 surrounds the front portion of the lamp D and extends partly around the two sides of the lamp as shown. All rays cast by D upon C are reflected back and upward upon A, and since the angle of incidence equals the 65 angle of reflection, the reflected rays are cast in a forward and downward direction toward the road bed.

The reflector A is surrounded by and inclosed within, a substantial weather-proof 70 housing, L, constructed of metal, and having the lower portion constructed to form a base R, by which the lamp may be fastened to the automobile or other vehicle, and having a front glass or lens N held in place by 75 the metal rim M, which also furnishes the lamp with a neat appearance.

Securely fastened by means of solder or other practical means to the case L, is the flanged portion J of the sleeve G. This 80 sleeve is of peculiar construction, being cylindrical on its outer surface and having the inner pointed bearing H and the opposite inner pointed bearing I, against which bearing rests the tube F. This construction 85 causes the tube to be engaged by the pointed bearings H and I, and the tube is held in proper relation to the sleeve by the pair of binding screws K and K', this construction, enabling the tube to be inclined and retained in an inclining position, or to be raised or lowered within the sleeve, thus changing the relative position of the lamp 90 D with regard to the reflector A, causing the rays of light to be focused or raised or 95 lowered upon the roadbed.

The tube is formed with an upper bayonet slot and a lower bayonet slot, both being designated by the letter Q in the drawing. These slots receive lugs on the lamp 100 base and the plug of the wire receiving socket O, respectively. Leading into and attached to O is the wire cable P containing the supply wires to the lamp D.

From the foregoing description taken in 105 connection with the drawings, it will be understood that the hood C acts as a reflector of the rays from the incandescent

lamp, casting them back and upward upon the main reflector A, which in turn reflects the rays out over and upon the road bed. It will also be noted that the tube may be 5 raised or lowered, or tilted in the sleeve to cause the lamp rays to be projected to a greater or less degree by the reflector.

It will be apparent that I provide means which will accomplish the objects of my 10 invention in a practical and efficient manner.

I claim:

1. In a headlight, a main reflector the upper portion thereof being constructed on a 15 semi-parabolic curve and the lower portion on a horizontal plane below the focal axis of the main reflector, a second curved reflector mounted at the front and upon the horizontal portion of the main reflector, a 20 source of light mounted in a vertical position between the main reflector and the second curved reflector, and means for adjusting the source of light vertically to raise

and lower it and on a horizontal axis to arrange the source of light either in a vertical or in an inclined position. 25

2. In an automobile lamp, the combination with a main reflector, a second reflector, a housing, a sleeve having a flanged end mounted in said housing and having its inner wall formed with a pair of oppositely disposed pointed bearings, a tube fitting in said sleeve and capable of a vertical and inclined adjustment upon said pointed bearings, binding screws in said sleeve engaging the tube to retain it in the proper position, a lamp carried by said tube partially surrounded by the hood shaped second reflector attached to the main reflector. 30

In testimony whereof I affix my signature in the presence of two witnesses.

LEWIS E. SANDSTROM.

Witnesses:

C. E. SANDSTROM,
JOHN S. GRENNEMAN.
